[57] CLAIM

The ornamental design for a portable multicompartment dispenser, as shown and described.

DESCRIPTION

FIG. 1 is a front perspective view of a portable multicompartment dispenser showing my new design, wherein;
FIG. 2 is a front elevational view;
FIG. 3 is a top plan view;
FIG. 4 is a rear elevational view;
FIG. 5 is a right side view, a view from the left side being a mirror image thereof; and,
FIG. 6 is a bottom plan view.
